US00D863144S

(12) **United States Design Patent** (10) Patent No.: **US D863,144 S**
(45) Date of Patent: **** Oct. 15, 2019**

(54) **GRILLE ELEMENT**(71) Applicant: **Oshkosh Corporation**, Oshkosh, WI (US)(72) Inventor: **Jesse Gander**, Oshkosh, WI (US)(73) Assignee: **Oshkosh Corporation**, Oshkosh, WI (US)(***) Term: **15 Years**(21) Appl. No.: **29/691,172**(22) Filed: **May 14, 2019****Related U.S. Application Data**

(63) Continuation of application No. 29/621,906, filed on Oct. 12, 2017, now Pat. No. Des. 856,860, which is a continuation of application No. 14/612,100, filed on Feb. 2, 2015, now Pat. No. 9,829,282, which is a continuation of application No. 13/629,009, filed on Sep. 27, 2012, now Pat. No. 8,943,946, said application No. 29/621,906 is a continuation of application No. 15/599,174, filed on May 18, 2017, which is a continuation of application No. 14/724,279, filed on May 28, 2015, now Pat. No. 9,656,640, which is a continuation of application No. 13/841,686, filed on Mar. 15, 2013, now Pat. No. 9,045,014.

(57) **CLAIM**

I claim the ornamental design for a grille element, as shown and described.

DESCRIPTION

FIG. 1 is a front perspective view of the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second front perspective view thereof; and,

FIG. 9 is a detailed front perspective view thereof.

Evenly-spaced broken lines depict unclaimed environmental subject matter. Dot-dash broken lines depict unclaimed boundaries of the claimed design.
